[57] CLAIM

The ornamental design for a clamping apparatus for repairing an automobile chassis, as shown and described.

DESCRIPTION

FIG. 1 is a perspective view of the clamping apparatus for repairing an automobile chassis showing my new design; an attachment bracket for use therewith is shown in phantom outline for purposes of illustrations only;

FIG. 2 is a front elevational side view thereof the rear side elevational view being a mirror image thereof;
FIG. 3 is a left side elevational view thereof;
FIG. 4 is a right side elevational view thereof;
FIG. 5 is a top plan view thereof; and,
FIG. 6 is a bottom plan view thereof.

The broken line showing of an attachment bracket in FIGS. 1 and 2 is for environmental purposes only and forms no part of the claimed design.
